UNITED STATES PATENT OFFICE

RUDOLPH J. SAILER, OF TOWNSLEY, NEW JERSEY, ASSIGNOR TO THE SINGER MANUFACTURING COMPANY, OF ELIZABETH, NEW JERSEY, A CORPORATION OF NEW JERSEY

WORK-GUIDE FOR SEWING MACHINES

Application filed June 8, 1931. Serial No. 542,765.

This invention relates to sewing machine work-guides and more particularly to work-guides of the type commonly known as a transverse binder which has a U-shaped strip-
5 guiding passageway formed at its delivery end with inclined strip-inverting edges which turn the strip outside-in as it is applied to the edge of the body-material being stitched. With work-guides of this and other
10 types it is often desirable to provide the sewing machine throat-plate with a clearance recess to permit the work-guide to be properly located in sewing position. For ordinary sewing, with the work-guide removed, this
15 recess serves no useful purpose and has a tendency to catch cross-seams and obstruct their free passage under the presser-foot.

The present invention has for an object to provide means for filling this recess in the
20 throat-plate when the work-guide is not in use. A further object of the invention is to provide a work-guide which is instantly shiftable into or out of sewing position and with which is associated a work-engaging
25 element for taking the place of the work-guide when the latter is not in use; the work-engaging element requiring no especial attention by the operator.

With the above and other objects in view,
30 as will hereinafter appear, the invention comprises the devices, combinations and arrangements of parts hereinafter described and particularly pointed out in the claims.

The features of the invention and the advantages attained thereby will be readily understood by those skilled in the art from the following detailed description of a preferred embodiment of the invention illustrated in the accompanying drawings in
35 which Fig. 1 is a top plan view of the device with the work-guide or binder in sewing position. Fig. 2 is a similar view with the binder retracted. Fig. 3 is a bottom plan view of the device with the binder partially retracted. Fig. 4 is a similar view with the binder fully retracted as in Fig. 2. Fig. 5 is a front side elevation, partly in section, of the device with the binder in sewing position. Fig. 6 is a similar view with the binder re-
40 tracted. Fig. 7 is a section on the line 7-7,
45

Fig. 8. Fig. 8 is a left-end elevation of the device and Fig. 9 is a sectional view of the device on the line 9-9, Fig. 3, but turned upright.

The invention is shown as embodied in a sewing machine having the cloth-plate 1, throat-plate 2, reciprocating needle 3 and presser-foot 4. The throat-plate is formed with the usual feed-dog slots 5 and needle-hole 6. The throat-plate is also formed in its upper or work-engaging face with a recess 7 disposed closely in advance of the needle-hole 6. The recess 7 is adapted to receive, in sewing position, the lower portion of the inclined U-shaped delivery end 8' of the transverse binder 8, as shown in Figs. 1 and 5; such binder being, in a broad sense, a work-engaging member or work-guide. The binder 8 has supporting feet 9 which are secured by screws 10 to the slide-plate 11 mounted on the upper side of the supporting plate 12 removably closing the aperture 13 in the cloth-plate 1. The plate 12 is seated upon a ledge 14 bordering the aperture 13 in the cloth-plate 1 and is held in place by means of the fixed and manually swingable spring-fingers, 15 and 16, respectively, which underlap the ledge 14.

The slide-plate 11 which carries the binder 8 is formed with a slot 17 which is entered by the stationary guide-block 18 fixed to the supporting plate 12. The binder is thus mounted on top of the plate 12 to slide laterally of the throat-plate 2 and transversely of the line of seam-formation from sewing position, Figs. 1 and 5, to retracted position, Figs. 2 and 6. One edge of the slide-plate 11 is notched at 19 to receive the tip end of a detent-spring 20 which yieldingly holds the binder 8 in sewing position.

Slidably mounted in the spaced guide-blocks 21 on the under side of the supporting plate 12 and directly below the binder 8 is a bar 22 to one end of which is screwed one end of the leaf-spring 23 the other end of which is thickened to form a filler-piece 24 adapted to occupy and fill the recess 7 in the throat-plate 2 when such recess is vacated by retraction of the binder 8. When the filler-piece 24 occupies the recess 7, its upper or

work-engaging and -supporting surface is flush with and forms a continuation of the work-supporting surface of the throat-plate. 2. The filler-piece 24 is formed on its under side with an inclined lifting surface 25, Fig. 5, which, during the movement of the filler-piece 24 to the left, engages the bottom edge 26 of the recess 7 and elevates the filler-piece 24 to its operative level in the recess 7, Fig. 10. 6. When the filler-piece 24 is retracted, it is also moved downwardly by its spring-shank 23, so as to be out of the way of the advancing delivery end 8' of the binder 8.

There is provided between the slide-plate 11 and the slide-bar 22, an interconnecting means comprising a lever 27 fulcrumed at 28 on the under side of the supporting plate 12. The lever 27 has a slot 29 in one end which is entered by a screw 30 carried by the slide-bar 22. The other end of the lever 27 is formed with a slot 31 which at times is entered by a coupling pin 32 carried by the vertically yielding spring-arm 33 secured to the slide-plate 11 which carries the binder 8.

25. The tongue 34, Fig. 9, at one side of the slot 31, stands at a higher lever than the lateral extension 35 at the other side of such slot. The coupling pin 32 has a rounded lower end which is projected into the slot 31 by the spring 33 far enough to engage the tongue 34 without danger of riding out of the slot 31 and over the upper face of the tongue 34 when the binder is being retracted. The lateral extension 35 of the lever 27 is disposed at a level such that there is a sufficiently positive engagement of the pin 32 with the adjacent side-wall of the slot 31 to retract the filler-piece 24 during the first part of the advancing movement of the binder 8. 40. When the filler-piece is fully retracted to the position shown in Fig. 9, the continued advancing movement of the binder 8 causes the rounded lower end of the pin 32 to ride over the corner of the slot 31 and across the upper face of the lateral extension 35 to the position shown in Fig. 1.

When the binder is retracted, the first part of the retracting movement causes the coupling pin to ride over the face of the lateral extension 35 of the lever 27 until it finds the slot 31 and drops into the latter, thereby coupling the binder 8 to the filler-piece 24 and causing the latter to be projected into the recess 7 in the throat-plate vacated by the delivery end of the binder.

Having thus set forth the nature of the invention, what I claim herein is:—

1. The combination with a sewing machine throat-plate having a recess in its upper surface, of a work-guide movable from a retracted position to a sewing position in which a portion of said guide is received in said recess, and means for filling said recess when said work-guide is retracted.
- 60 2. The combination with a sewing machine

throat-plate having a recess, of a work-guide movable from a retracted position to a sewing position in which a portion of said guide is received in said recess, and automatic means for filling said recess when said work-guide is retracted. 70

3. The combination with a sewing machine throat-plate having a recess in its upper surface, of a work-guide movable from a retracted position to a sewing position in which a portion of said guide is received in said recess, and means connected to said work-guide for filling said recess when said work-guide is retracted. 75

4. The combination with a sewing machine throat-plate formed with a needle-hole and a recess in its upper surface in advance of said needle-hole, of a pair of interconnected reciprocally movable work-engaging members alternately received in said recess. 80

5. The combination with a sewing machine throat-plate formed with a needle-hole and a recess in its upper surface in advance of said needle-hole, of a pair of slidably mounted work-engaging members adapted for alternate reception in said recess. 85

6. The combination with a sewing machine throat-plate formed with a needle-hole and a recess in its upper surface in advance of said needle-hole, of a pair of movably mounted work-engaging members adapted for alternate reception in said recess, and means interconnecting said members to cause one member to be moved in one direction when the other member is moved in another direction. 90

7. The combination with a sewing machine throat-plate having a needle-hole and a recess in its upper surface in advance of said needle-hole, of a binder having a strip-inverting delivery end partially received in said recess, said binder being retractible from said recess transversely of the line of seam-formation, and means connected to said binder for filling said recess when said binder is retracted. 105

8. The combination with a sewing machine throat-plate having a recess in its upper face, of a filler-piece for said recess movable laterally of said throat-plate and vertically relative to the plane of said throat-plate. 110

9. The combination with a sewing machine throat-plate having a recess, of a work-guiding element and a filler-piece element adapted for alternate occupancy of the space within said recess, one of said elements being movable vertically relative to the plane of said throat-plate. 115

10. The combination with a sewing machine throat-plate having a recess, of a work-guiding element and a filler-piece element adapted for alternate occupancy of the space within said recess, both of said elements being mounted for movement laterally of said throat-plate and one of them being movable 120

vertically relative to the plane of said throat-plate.

- 5 11. In a sewing machine work-guide, a supporting-plate, a plurality of work-engaging members movably carried by said plate, and a pivoted element interconnecting said members to cause them to move simultaneously in opposite directions.
- 10 12. In a sewing machine work-guide, a supporting-plate, a plurality of work-engaging members slidably mounted on opposite sides of said plate, and a pivoted lever interconnecting said members to cause them to move simultaneously in opposite directions.
- 15 13. In a sewing machine, the combination with a reciprocating needle and a throat-plate having a recess in its upper face, of a filler-piece in said recess, a work-guide mounted for movement from a retracted position to a sewing position in which it is partially received in said recess, and means interconnecting said work-guide and said filler-piece and including an automatic coupling and uncoupling device for withdrawing said filler-piece
- 20 23. from said recess during the first part of the advancing movement of the work-guide and permitting the filler-piece to dwell in retracted position during the last part of the advancing movement of the work-guide.
- 25 30. 14. The combination with a supporting-plate adapted for attachment to the cloth-plate of a sewing machine and having a binder-head retractably mounted thereon, of a work-supporting element also carried by said plate and adapted for advancement to the position vacated by said binder-head.

In testimony whereof I have signed my name to this specification.

RUDOLPH J. SAILER.
